UNITED STATES PATENT OFFICE.

HENRY CLINTON HICKS, OF MINNEAPOLIS, MINNESOTA.

STOCK-CAR.

SPECIFICATION forming part of Letters Patent No. 338,741, dated March 30, 1886.

Application filed September 12, 1885. Serial No. 176,974. (No model.)

To all whom it may concern:

Be it known that I, HENRY CLINTON HICKS, a citizen of the United States, and a resident of Minneapolis, in the county of Hennepin 5 and State of Minnesota, have invented certain new and useful Improvements in Stock-Cars for Swine, Sheep, &c., of which the following is a specification.

This invention relates to that class of stock-cars adapted to the transportation of swine, sheep, and similar-sized animals; and it consists in the construction, combination, and arrangement of parts, as hereinafter shown and described.

15 In the drawings, Figure 1 is a sectional side elevation of one-half of a stock-car, showing my improvements arranged therein. Fig. 2 is a plan view of Fig. 1, with the central portion of the floor broken out for convenience in drawing. Fig. 3 is a cross-section on the line $x-x$ of Fig. 1, showing one section of the auxiliary folding deck or floor in place ready for use. Fig. 4 is a sectional detail of one side of the car, similar to that shown in Fig. 3, with 25 the folding deck elevated. Figs. 5 and 6 are enlarged details illustrating the construction and mode of application of the combined folding-deck support and drainage-tubes. Figs. 7 and 30 8 are enlarged sectional details illustrating some slight variations in the manner of constructing and operating the folding slatted belt, &c.

A' is the main floor, B the stanchions or frame-work, C the roof, and D the doorway-35 openings, of a stock-car of the ordinary construction.

Stock-cars in which it is intended to transport swine, sheep, and similar-sized animals are usually formed with an auxiliary deck or 40 floor about midway between the main deck and the roof, on which an additional stock of animals is carried, and the manner of forming this auxiliary deck, whereby it may be folded up out of the way when not in use, and also 45 the arrangement, in combination with said folding auxiliary deck, of adjustable partition-bars, whereby the car may be formed into a number of separate compartments, constitutes the main feature of my invention.

50 The auxiliary deck may be formed in any desired number of sections; but generally it

will be found convenient to form it into eight sections—four on each side of the doorway-openings D—as shown in the drawings.

E' E² represent a contiguous pair of the auxiliary deck or floor sections, each hinged, or otherwise suitably connected by one edge, a', to the stanchions B, on opposite sides of the car, and with their other edges, a³ a⁴, rabbeted in opposite relations, as shown in Figs. 3 and 5, so that when the two sections are folded down, as in Fig. 3, the rabbet of the section E² will underlap the rabbet of the other section, E', and thus support it, so that a supporting leg or legs, F, will be required only under the sections E². The stanchions B will be formed with the parts below the hinges a', projecting inward to form shoulders, on which the edges of the deck-sections rest, to provide additional support to the sections, and prevent the whole strain coming upon the hinges a'. Under some circumstances the hinges a' might be dispensed with, and the edges of the sections E' E² supported only by the projections of the stanchions B; but generally both the hinges and projections will be used.

E³ E⁴ represent two other contiguous deck-sections, arranged in the car in the same manner as the sections E' E², the two sets of sections occupying all the space between the doorway-openings D and the end of the car, and forming, when turned down, a complete auxiliary "deck" to one-half of the car.

Each end of the car will be provided with its own set of deck-sections; but as both ends of the car will be arranged precisely alike, I have shown only one end as being sufficient to fully illustrate the invention.

The rabbet in the sections E² and E⁴ will be provided with a small channel or groove, b, (see Figs. 3, 5, and 6,) and each contiguous pair of the sections will be inclined downward slightly toward each other, so that all liquid excrement will flow down toward the center into the groove b, which thus acts as a gutter to carry it off and prevent its falling upon the animals on the floor A'. The supporting-legs F will be formed tubular, and will be attached to the sections E² E⁴ by hinges d, so that they can be folded up against the bottoms of the sections and held by hooks e or other means, as shown in Figs. 1, 2, and 4. When the sec-

tions are folded up or turned downward, with their lower ends, g , inserted into cavities in the floor A' , to support the sections, as shown in Figs. 1, 3, and 5, being tubular, these legs 5 F will be utilized as conduits to convey the liquids running into the channels b downward through the floor A' , and to insure them more perfect action in this respect their upper ends will be enlarged, as at h , and perforations 10 formed through the channels b above these enlargements, by which the contents of the channels will flow into the tubular support F and be conveyed therein down through the floor A' .

15 Opposite the joint between the ends of the deck-sections $E' E^2$ and $E^3 E^4$, and also opposite the ends of the sections $E^3 E^4$ next the doorway-openings D , the stanchions or side frames are arranged in pairs, only a few inches 20 apart, as shown at B^2 , and above each of these pairs of stanchions is pivoted a chain-pulley, H' , and in the lower part of the space between each pair is journaled a small chain sheave or carrier, H^2 , each of the latter being directly 25 in line below one of the chain-pulleys H' , so that chains H^3 may be run from the chain-pulleys H' down around their respective sheaves H^2 . Running across the car and journaled by their ends in the upper part of the 30 side frames are a series of horizontal shafts, H^4 —one above each set of the deck-sections $E' E^2$ and $E^3 E^4$ —and each shaft carrying a chain-sheave, H^5 , on each end in line with one of the chain-pulleys H' , so that the chains H^3 35 will "lead" from the pulleys H' to the pulleys H^5 , as shown. Near each of the sheaves H^5 , and slightly to one side and with its center a short distance below the center of the sheave H^5 , is a small carrier, H^7 , over which the chain 40 H^3 leads to the sheave H^5 .

On the journal of each of the sheaves H' , and inside them, is pivoted loosely a carrier, H^8 , over which the chain H^3 leads from the carrier H^2 , and from thence to the carrier H^7 . 45 The carriers H^7 are set slightly at an angle, to properly guide the chains from the carriers H' to H^8 , and it may also be found necessary to set the carriers H^2 at an angle; but generally such a slight deviation from a true line as 50 that required can be made without causing the chains to run off from the sheaves. Each opposite pair of the chains H^3 will be connected at intervals by slats H^9 , each opposite pair of the chains and its connecting-slats 55 thus forming an endless slatted belt adapted to be rolled up until the slats lie along horizontally beneath the roof C , as shown at the right of Figs. 1 and 2, or run down to divide the car into separate pens, as shown at the 60 left of Figs. 1 and 2.

In Figs. 7 and 8 I have shown enlarged detail views illustrating a slight variation in the manner of operating the slatted belts. This 65 consists in connecting to the chains or cables H^3 at m smaller cables or chains, H^{10} , the slats H^9 being attached to these latter cables instead of the main chains or cables H^3 , as in Figs. 1

and 2. Upon each of the pivots of the wheels or pulleys H' , I arrange an additional pulley or carrier, H^{11} , somewhat larger than the pulleys H' , over which larger pulleys, H^{11} , the slats H^9 are adapted to run to hold them outward away from the chains or cables H^3 , so that the slats will not "cramp" in passing over the pulleys. By these simple arrangements of the 75 auxiliary deck-sections and the endless slatted belt the car can be divided into two compartments or "floors" horizontally, and these floors subdivided into pens perpendicularly, to divide the stock into separate lots. This 80 is a great convenience in shipping stock, as it enables the shipper to keep the animals more separated, and also enables him to handle and control them more easily. It also enables the shipper to keep sheep and swine separated, 85 or the large animals separate from the small ones. Another great advantage gained by this arrangement is, that all the auxiliary floors and slatted dividing-belts may be folded up out of the way, and the car left entirely 90 unobstructed for use for transporting ordinary freight.

By setting the carriers H^7 in the position shown I gain two important advantages: first, the chain H^3 is thereby caused to encircle more of the surface of the sheaves H^5 , and consequently the friction is increased, so that less danger of slipping exists; and, second, the lower section of the horizontal part of the chain H^3 is held at a higher point than it 100 could otherwise be, so as to be more out of the way of freight when the car is used for freight, and also allow more room for folding up of the auxiliary deck-section.

Parallel with the upper surface of each of 105 the upper horizontal sections of the chains H^3 is a bar, L , supported in any suitable manner to the frame of the car, and adapted to support the ends of the slats H^9 , so that their weight will not sag the chains downward when 110 they are elevated, as shown at the right of Figs. 1 and 2.

Along the sides of the car, between the stanchions $B' B^2$, at suitable intervals, will be arranged a series of drinking-cups, K' , connected together at their bottoms by pipes d' , and the cups nearest the ends of the car connected by pipes d^2 to a reservoir, K^2 , across the end of the car, so that when water is poured into the reservoir K^2 it will run through the 120 pipes $d^2 d'$ into the cups K' , so that the animals may be supplied with water from the outside of the car, and without removing them from the car.

Having thus described my invention, what 125 I claim as new is—

1. In a stock-car, the stanchions or side frames, B , provided with inwardly-projecting lower portions adapted to support and carry the outer edges of folding auxiliary deck-sections $E' E^2$ and $E^3 E^4$, substantially as shown and described, whereby said deck-sections may be folded up against the sides of the car to leave the interior of the car unobstructed.

for use in transporting freight, and folded down horizontally to form a floor or deck in said car between its main floor and the roof, for the transportation of animals.

5 2. In a stock-car, the stanchions or side frames, B, provided with inwardly-projecting lower portions adapted to support and carry the outer edges of folding auxiliary deck-sections E' E² and E³ E⁴, the inner contiguous edges of said auxiliary deck-sections being rabbeted in opposite relations and provided with hinged supporting legs F, substantially as set forth.

15 3. In a stock-car, an auxiliary deck or floor intermediate between the main floor and roof, said deck being composed of inclined folding sections, and said sections being provided with gutters at their lower ends, in combination with hollow legs which support the lower 20 ends of the folding sections, and which communicate with said gutters, substantially as and for the purpose set forth.

25 4. In a stock-car, sheaves H', H², H⁵, and H⁸, said sheaves H' and H⁸ being concentric with each other, and endless stall-bar carrying cables which pass consecutively around sheaves H', H⁵, H⁸, and H² back to sheaves H', in the order named, in combination with angularly-set sheaves or carriers H¹, mounted between

sheaves H⁵ and H⁸, which lead the cables from 30 sheaves H⁵ to sheave H⁸, substantially as set forth.

5. In a stock-car, endless cables which support and carry transverse stall-bars, and which run over suitable sheaves, whereby said stall-bars may be raised and lowered across the car, in combination with horizontal bars fixed to the upper part of the car, which support the ends of said stall-bars when the same are elevated, substantially as set forth. 35 40

6. In a stock-car, endless cables which run over suitable sheaves, short cables attached at their ends to said endless cables, and transverse stall-bars secured to said short cables, and adapted to be raised and lowered across 45 the car by means of said endless cables, in combination with disks or carriers H¹¹, which support the ends of said stall-bars when said bars are being raised or lowered, substantially as set forth. 50

In testimony whereof I have hereunto set my hand in the presence of two subscribing witnesses.

HENRY CLINTON HICKS.
